United States Patent

Des. 239,757

Patented May 4, 1976

239,757

POUR-IN TYPE BEVERAGE MAKER

John C. Martin, Springfield, Ill., assignor to
Bunn-O-Matic Corporation

Filed Sept. 17, 1974, Ser. No. 506,877

Term of patent 14 years

Int. Cl. D7—02

U.S. Cl. D7—62

Fig. 4

Fig. 5

Fig. 6

Fig. 7

FIG. 1 is a perspective view looking from the top, front and left sides of a pour-in type beverage maker embodying my new design;

FIG. 2 is a top plan view;

FIG. 3 is a side elevational view;

FIG. 4 is a front elevational view;

FIG. 5 is a horizontal sectional view along line 5—5 of FIG. 4 looking in the direction of the arrows;

FIG. 6 is a rear elevational view on a reduced scale; and

FIG. 7 is a bottom plan view on a reduced scale.

I claim:

The ornamental design for a pour-in type beverage maker, substantially as shown and described.
